The ornamental design for an ultraviolet sterilization device, as shown and described.

DESCRIPTION

FIG. 1 is an overhead, front and side, perspective view of an ultraviolet sterilization device according to our new design. FIG. 2 is an underneath, rear and side, perspective view thereof.

FIG. 3 is a left side elevation view thereof.

FIG. 4 is a right side elevation view thereof.

FIG. 5 is a top plan view thereof.

FIG. 6 is a bottom plan view thereof.

FIG. 7 is a front elevation view thereof; and,

FIG. 8 is a rear elevation view thereof.

The broken lines shown in the drawings depict portions of the ultraviolet sterilization device that form no part of the claimed design.
